UNITED STATES PATENT OFFICE.

ARTHUR H. DODGE, OF NEW YORK, N. Y., ASSIGNOR TO THE J. G. WILSON CORPORATION, OF NEW YORK, N. Y., A CORPORATION OF VIRGINIA.

OFFSETTING SUPPORT FOR VENETIAN BLINDS.

Application filed February 8, 1923. Serial No. 36,780.

This invention relates to improvements in mountings for Venetian blinds whereby when such blinds are used adjacent windows having the fenestra sash, or one in which one or more sections swing upon horizontal axes, the Venetian blind may be readily adjusted to different positions away from the window to permit the movable section of the window to be opened to any desired extent without 10 in any way interfering with the blind or with its usual mode of operation.

One object of the present invention is to provide Venetian blinds with an improved mechanism for movably supporting the 15 blinds to enable the same to be readily and conveniently adjusted to accommodate windows of the above mentioned type.

Another object of the invention is to provide such a structure wherein the Venetian 20 blind may be operated in the usual manner in so far as adjustment of the blind itself is concerned, while at the same time providing a most convenient and efficient arrangement for moving the blind to its various 25 positions and maintaining the blind in a vertical position whatever may be its relative position in respect of the window with which it is used.

Various advantageous features of the invention will become apparent from the following description when taken in connection with the accompanying drawings, in which—

Figure 1 is a front elevation of a preferred form of construction;

Figure 2 is a top plan view thereof;

Figure 3 is a sectional view on line 3—3, Figure 1, showing the blind adjusted away from the window;

Figure 4 is a similar view on line 4—4, Figure 1, showing the position the parts occupy when the blind is adjusted in position close to the window;

Figure 5 is an enlarged front elevation 45 of the bracket shown in the upper right-hand portion of Figure 1;

Figure 6 is a left-hand side elevation thereof;

Figure 7 is a front elevation similar to Figure 1 but showing a somewhat different construction of supporting means for the blind;

Figure 8 is a sectional view of this modified construction showing the blind at its position farthest from the window;

Figure 9 is a similar view showing the

blind in its position closest to the window;

Figure 10 is a detailed sectional view illustrating one of the supporting brackets and rollers for the supporting bar of the blind;

Figure 11 is an end elevation of the parts 60 shown in Figure 10; and

Figure 12 is a side elevation of the upper portion of the blind and supporting bracket.

Referring to the drawings and particularly to Figures 1, 3 and 4, the Venetian 65 blind itself consists of the top bar 1 and a number of slats 2 which are all connected together and to the top or tilting bar 1 by tapes 3 which are secured to one side of the bar 1 and to the edges of all of the slats, as is usual in Venetian blind construction. In order that the objects of the invention may be accomplished the Venetian blind is supported solely at its top whereby it may be moved to various positions toward and from 70 the window adjacent to which it is hung and at the same time maintain its vertical position and be operable in the ordinary way for raising and lowering the blind and changing the angle of the slats as desired. 80

In the preferred form of the invention this mounting of the blind and its adjustability toward and from the window is accomplished by providing a second or supporting bar 4 mounted above the tilting 85 bar 1 and pivotally connected thereto. This connection is preferably effected by means of an angle iron 5 engaging the under side of the right-hand end of the supporting bar 4 and an angle iron 6 engaging the under side 90 of the left hand end thereof. Pintles, extending from the bar 1, enter holes, one in each angle iron, so that said bar may rock upon said pintles and thereby change the angular position of its slats 2. The means 95 whereby the bar 1 is rocked is accomplished with the usual cord 7 and preferably this cord passes over a roller 8 which is carried by a bracket 9 supported on the under side of the bar 4 near its left-hand portion, as shown in Figure 1, the ends of the cord being connected to the top and bottom respectively of the bar 1, whereby pulling the outer strand of the cord 7 causes the slats to be rocked in one direction, while the opposite 100 direction of movement is effected by pulling the other strand of the cord, as will be readily understood.

The adjustment of the Venetian blind toward and from the window is preferably 110

2
effected by means of arms 10, one on either side of the blind, which arms pivotally support the bar 4 at upper ends of the arms, brackets 11 being provided for this purpose, 5 and also pivotally engage brackets 12 at their lower ends, Figure 1. By this arrangement it will be understood that as the arms 10 are moved outwardly the Venetian blind also moves outwardly but always maintains 10 its vertical position, being freely suspended from its top portion only. When the blind is closest to the window as in Figure 4, the arms 10 are not quite vertical but are slightly inclined away from the window so that the 15 weight of the blind is enough to cause further movement away from the window when such movement is permitted by the means which normally restrain the blind from movement and which means will now be described.

20 Preferably there is provided a chain or cord, the two portions of which 13 and 14 are connected to the bar 4, the portion 13 near the left-hand end and the portion 14 near the right-hand end of said bar. The portion 13 passes through a sheave 15 of a bracket 16 and over a roller 17 in a bracket 18. This latter bracket also carries a roller 19 situated in a different vertical plane from 25 the roller 18, as shown clearly in Figure 6, and the end 14 of the cord after passing over a sheave 20 carried by a bracket 21 passes over said roller 19 below which said two ends of the cord are united in a loop. 30 The loop is formed by a ring 22 secured to the two strands of the cord, such ring forming a stop to limit the movement of the blind away from the window. Preferably the bracket 18 has a recess or depression 35 in its underside with which the ring 22 engages. The cord 24 is secured to the loop and is manipulated manually to adjust the blind toward and from the window.

40 It is desired to avoid noise and jar when the blind is brought up adjacent the window and to accomplish this I have provided cushioning means in the form of bumpers 25 and 26 secured to the bar 4 and so positioned that they will contact respectively with abutments 27 depending from the brackets 50 16 and 21.

45 The Venetian blind itself is moved up and down to shorten or lengthen the blind by the usual cords 28 which are secured to the bottom slat and which pass about guide rollers on the bar 4 and depend for convenient manipulation at the right side of the blind as shown at 29. The window frame is shown somewhat diagrammatically, the 55 top portion thereof being indicated at 30 and the swinging sash portion at 31 pivoted on a horizontal axis 32 whereby it may swing, as shown in Figure 3.

60 With the construction described a very 65 convenient and efficient means has been pro-

vided whereby the blind may be adjusted to different positions parallel with the window to accommodate it of the degree of opening to the swinging portion 31 of the window and at the same time provide for 70 manipulation of the blind in the usual way, in any position.

In Figures 7 to 12, I have shown a slightly modified construction and one which differs from that just described principally in 75 the fact that instead of providing the swinging arms 10 there is provided a bracket 33 and a bracket 34, one at each side of the blind, and secured in any suitable manner adjacent to the window frame. One of these 80 brackets 33 is shown in enlarged elevation in Figure 12, wherein it will be seen that the same is provided with a slot for supporting and adjusting the blind in its various positions. As in the first described construction, the top bar 35 of the Venetian blind is pivotally connected in the same manner as already described, to the second bar 36, but the manner in which this second bar 36 is mounted for adjustment is different. 85 At each end this bar is provided with an angle piece 37 secured by screws 38 to the bar 36. A stud 39 is screw-threaded or otherwise secured in one arm of the angle member and is provided preferably with a 90 hexagonal portion 40 forming an abutment to engage the angle member, whereby it may be securely screwed to said member. A flanged roller 41 is mounted on the stud 95 and is held in place by means of a screw 42, 100 said screw engaging internal threads in the head of the stud. As shown in Figure 12, the bracket 33 is provided with a slot 43 which is enlarged at its right end 44, the enlargement being of such size that the 105 roller 41 may be inserted therethrough so that the flanges of the roller may then engage on opposite sides of the track portion of the bracket, after which the screw 42 is inserted. The cord connections, whereby 110 the blind is adjusted toward and from the window, and whereby the blind is moved to lengthen or shorten the same, and to change the angular position of its slats, are the same 115 as in the first described form.

120 It is to be understood that variations may be resorted to within the spirit of the invention as described, without departing from the spirit thereof.

Having thus described my invention, I 125 desire to secure by Letters Patent—

1. In a construction for Venetian blinds, in combination a slat structure comprising a series of parallel slats, means for connecting said slats, supporting means for the slats adjustable toward and from a window adjacent to which the slat structure is hung, and means pivotally connecting said supporting means to the slat structure at its top only, 130 whereby said slat structure may hang ver-

tically in any of its various positions to which said supporting means may be adjusted.

2. In a construction for Venetian blinds, in combination a supporting bar, a tilting bar pivotally suspended upon said supporting bar, a series of parallel slats, means for connecting said slats and for suspending the same upon the tilting bar for tilting movement therewith, and means for mounting the supporting bar for movement from and toward a window.

3. In a structure for offsetting Venetian blinds, the combination with a Venetian blind, of means for supporting the same at its top only adjacent a window frame, brackets at the top of the window frame, sheaves carried thereby, cords engaging said supporting means and passing through said sheaves for adjusting said blind toward and from a window, said brackets having each an abutment and bumpers carried by said supporting means for engaging said abutments when the blind is moved up close to the window.

4. In a structure for offsetting Venetian blinds, the combination with a Venetian blind, of means for supporting the same at its top only adjacent a window frame, brackets at the top of the window frame, sheaves carried thereby, cords engaging said supporting means and passing through said sheaves for adjusting said blind toward and from a window, another bracket carrying two sheaves in different vertical planes, and a ring secured to said cords below said sheaves, said second bracket having a recess to receive said ring which acts as a stop to limit the movement of the blind away from the window.

5. In a structure for Venetian blinds, in combination, a supporting bar, a tilting bar pivotally suspended from the supporting bar, a series of parallel slats, means for connecting the slats and for suspending the same from the tilting bar for tilting movement therewith, means for mounting the supporting bar for adjustment toward and from a window, a bracket carried by the supporting bar, a roller mounted in the bracket, and a cord passing over the roller and secured to the tilting bar in a manner to rock the same on its pivotal supports.

6. In a structure for Venetian blinds, in combination, a supporting bar, a tilting bar pivotally suspended upon the supporting bar, a series of parallel slats suspended from the tilting bar, connections between said slats and the tilting bar for tilting the slats from the tilting bar, means for mounting the supporting bar for adjustment toward and from a window, guide rollers carried by the supporting bar, and cords for raising and lowering the slats passing about said guide rollers.

7. In a structure for Venetian blinds, in

combination, a supporting bar, a tilting bar pivotally suspended from the supporting bar, a series of parallel slats and means for suspending the slats from said tilting bar and for connecting the same for tilting movement therewith, means for mounting the supporting bar for adjustment toward and from a window, guide rollers carried by the supporting bar, cords for raising and lowering the slats passing about said guide rollers, a bracket carried by the supporting bar, a roller mounted on the bracket and a cord passing over the roller and attached to the tilting bar in a manner to rock the same on its pivotal supports.

8. In an offsetting Venetian blind structure, the combination with pivotally mounted supporting arms, of a Venetian blind pivotally connected to said arms at its top only whereby said blind may occupy different vertical positions parallel to a window frame as said arms swing to different positions.

9. In an offsetting Venetian blind structure, the combination with supporting arms pivoted at their lower ends with relation to a window frame, of a Venetian blind pivotally connected to the upper ends of said arms at its upper end only and suspended from said arms in a substantially vertical position.

10. In an offsetting Venetian blind structure, the combination with a Venetian blind having the usual top bar and movable slats, of a second bar above the first, means pivotally connecting the two bars, supporting arms one on each side and pivotally connected with a window frame and also pivotally connected with said second bar whereby said blind may occupy different vertical positions parallel to the window frame as said arms swing to different positions.

11. In a Venetian blind construction, in combination with a slat structure comprising a series of parallel slats, means for connecting said slats, means for supporting the slat structure at its top only adjacent a window frame so that it may be adjusted toward and from said frame, brackets at the top of the window frame, each having an abutment, and bumpers carried by said supporting means for engaging said abutments to limit the inward movement of the slat structure.

12. In a construction for Venetian blinds, in combination a slat structure comprising a series of parallel slats, means for connecting said slats, means for supporting the slat structure at its top only adjacent a window frame so that it may be adjusted toward and from the frame, cords for adjusting the slat structure toward and from the window frame, and a stop attached to said cords to limit the movement of the slat structure away from said frame.

13. In a Venetian blind structure, in combination, a supporting bar, a tilting bar piv-

totally suspended from the supporting bar, a series of parallel slats, means for connecting said slats and for suspending the same from the tilting bar so that the slats will tilt with said bar, and means for pivotally suspending the supporting bar for adjustment toward and from the window so that the blind will

hang substantially vertically from said supporting bar in every position in which said bar may be adjusted.

Signed at New York this 28 day of January 1926.

ARTHUR H. DODGE.
